(57) **CLAIM**

The ornamental design for a phone holder, as shown and described.

DESCRIPTION

FIG. 1 is a front view thereof;
FIG. 2 is a rear view thereof;
FIG. 3 is a left-side view thereof;
FIG. 4 is a right-side view thereof;
FIG. 5 is a top plan view thereof;
FIG. 6 is a bottom plan view thereof; and,
FIG. 7 is an isometric perspective view of the phone holder.
The broken lines showing fasteners are included for the
purpose of illustrating environmental structure and form no
part of the claimed design.
